UNITED STATES PATENT OFFICE.

PHILLIP EBELING, OF MOUNDSVILLE, WEST VIRGINIA, ASSIGNOR OF ONE-HALF TO
J. W. LAMPARTER, OF MOUNDSVILLE, WEST VIRGINIA.

DESIGN FOR A GLASS FOR HEADLIGHTS.

50,938.

Specification for Design.

Patented June 19, 1917.

Application filed January 2, 1917. Serial No. 140,329. Term of patent 7 years.

To all whom it may concern:

Be it known that I, PHILLIP EBELING, a citizen of the United States, residing at Moundsville, in the county of Marshall and State of West Virginia, have invented a new, original, and ornamental Design for Glasses for Headlights, of which the following is a specification, reference being had to the accompanying drawings, in which—

Figure 1 is an edge view of the invention;

Fig. 2 is a rear elevation of the same; and—

Fig. 3 is a central section.

I claim:

The ornamental design for a glass for headlights, as shown.

PHILLIP EBELING.

Witnesses:

W. J. SHAW,

A. W. KOENEMUND.
